CLAIM

The ornamental design for a drinking cup for arthritic persons, as shown and described.

DESCRIPTION

FIG. 1 is an isometric view of the drinking cup for arthritic persons showing my new design;

FIG. 2 is a side, elevational view thereof, with the other side elevational view being a mirror image;

FIG. 3 is a top view thereof;

FIG. 4 is a rear view thereof;

FIG. 5 is a front view thereof; and,

FIG. 6 is a bottom view thereof.

The broken-line showing of three hands in FIG. 3 is for illustrative purposes only and forms no part of the claimed design.

FIG 2

FIG 1

FIG 3

FIG 4

FIG 5

FIG 6
